UNITED STATES PATENT OFFICE.

FRANK C. RINSCHE, OF DETROIT, MICHIGAN, ASSIGNOR TO BURROUGHS ADDING MACHINE COMPANY, OF DETROIT, MICHIGAN, A CORPORATION OF MICHIGAN.

ADDING-MACHINE.

1,234,218.

Specification of Letters Patent. Patented July 24, 1917.

Application filed September 15, 1914. Serial No. 861,772.

To all whom it may concern:

Be it known that I, FRANK C. RINSCHE, a citizen of the United States, residing at Detroit, in the county of Wayne and State 5 of Michigan, have invented certain new and useful Improvements in Adding-Machines, of which the following is a specification.

The present invention relates more especially to that class of adding machines 10 known in the trade as "visible," which term has reference to the matter of recording in such manner that the operator can see the work as it proceeds, much as in the case of typewriting machines, having the so-called 15 "front strike" characteristic.

The principal object of the invention is to protect the type carriers against accumulation of dust and dirt and consequently interference with the proper action of the type 20 carriers besides the filling in of depressions in the faces of the type so that the desirable sharp impressions in the printing are not had. It will be understood that in an adding machine of the so-called "visible" class 25 the type carriers in being set are projected through an opening in the casing of the machine. It is through such an opening that dust and dirt reaches the type carriers. In carrying out my invention I provide for 30 automatically opening and closing the casing so that dust and dirt will be excluded. Thus I supply a closure for the opening in the casing and arrange for its being thrown back as a preliminary to projection of the 35 type carriers through the opening and then for its being restored to closing position at the conclusion of the operation. Incidentally I utilize the closure as a line finder and gage.

40 I have here illustrated my invention as applied to the adding and listing machine known upon the market as the "Burroughs Visible," which machine is in the main a redesign of an adding and listing machine 45 heretofore known upon the market as the "Pike." The general characteristics of the latter are well understood by those skilled in the art. Reference may be had in this connection to Patent 763,692 issued June 28, 50 1904, and to Patent No. 955,789, issued January 19, 1910.

In the drawings which accompany and form part of this specification, Figure 1 represents in vertical section the rear portion of

a machine of the kind referred to, having incorporated therein a preferred form of means for carrying out my present invention; Fig. 2 illustrates some of the same parts in changed relationship which results from operation of the machine; Fig. 3 is a 60 cross section taken substantially on line 3—3 of Fig. 1; Fig. 4 is a partial top plan view under normal conditions such as illustrated in Fig. 1; Fig. 5 is a similar view under conditions such as illustrated in Fig. 2. 65

The machine proper corresponds in the main with that illustrated in the above mentioned patents though differing therefrom in particulars of the hammer controlling mechanism and in certain relationship of 70 parts established for the purpose of presenting the recording work to the operator's vision as it proceeds. Thus the type carrying levers 2 which pivot upon the rock shaft 3 have a contour and disposition which provides for a front strike of the types 4 against the roller platen 5 when said types are driven by hammers 6. The casing of the machine is correspondingly constructed, that portion thereof which incloses the hammer 80 heads and is designated by the numeral 7, being elevated just sufficient for such purpose and being sloped downwardly toward the roller platen so that the operator of the machine when standing or seated in front 85 of the machine, may have an unobstructed view of the platen just above the printing line, it being understood that the line-space feed occurs in an operation of the machine after the printing so that the imprint moves 90 up into the operator's line of vision. The upper central portion of the frame piece 7 is in the form of a housing with sides 7^a beyond which the ink ribbon spools 8 are arranged upon the depressed portions of this 95 frame piece in the usual manner so that the ink ribbon 9 stretches across the rear open end of this housing as best illustrated in Fig. 5, guiding posts 10 being located just beyond the sides 7^a of the latter. The top 100 of the housing is open adjacent the platen, at 7^b, sufficiently for the free projection therethrough of the segmental type carrying arms of the levers 2. It is through this opening that dust and dirt is apt to fall and 105 when accumulation thereof occurs on the oily sides of the type carriers a gummy substance forms which interferes with the free

action of the type carriers and is known to prevent a proper positioning of them. Furthermore the faces of the type 4 fill so that sharp imprints are not had.

5 In carrying out my invention in the form here shown, I keep this opening closed, except when the type carriers are in action, by a curved plate 11 whose rear edge is normally in close proximity to the ink ribbon 9 where the latter runs closely adjacent the roller platen 5, as shown in Fig. 1, while its front edge slightly underlaps the housing top. In lateral extent this plate corresponds with the width of the housing and 15 it is preferably formed integral with side arms 11^a lying closely adjacent the housing sides 7^a, as shown in Fig. 3, and extending down to a cross rod 12 on which they pivot. The plate 11 and the side arms 11^a thus constitute a yoke which may swing upon said 20 cross rod. The latter is a familiar element of the machine proper and constitutes a pivotal support for a hammer-restoring bail 13 and also for the hammers 6. The side arms 25 11^a of the said yoke have a gooseneck formation to accommodate the customary swing of said bail. A spring 14 which connects one of the side arms 11^a with a frame stud 15 operates to normally hold the yoke rearward with the rear edge of the plate 11 30 against the platen as shown in Fig. 1.

I provide for retraction of the above described closure yoke through appropriate connection with the actuating mechanism of 35 the machine. This comprises a crank handle 16 on a rock shaft 17 carrying a crank arm 18 connected by a link 19 to a full-stroke sector 20 secured to a rock shaft 21 which has a crank arm 22 connected by link 23 with a 40 crank arm 24 on a rock shaft 25 carrying a cam plate 26. The latter serves the usual functions of rocking the hammer restoring bail and the familiar type-carrier restoring bail 27 which is secured to the rock shaft 3 45 and normally restrains the type-carrying levers 2 in opposition to springs whose function is to project the segmental type housings through the opening 7^b. I utilize the oscillation of the hammer-restoring bail 13 50 to control the closure yoke. To this end I mount a roller stud 30 upon the left side arm 13^a of said bail and hang from a frame stud 31 a rocker piece 32 to be operated upon by said roller stud and to operate in turn 55 upon the yoke. This rocker piece has a concave edge 32^a normally hugging the roller 30 as shown in Fig. 1, under enforcement of the spring 14, one of the yoke side arms 11^a having a stud 33 which bears upon an 60 upper straight edge of the rocker piece. The latter is of somewhat fan-shaped form and has an extension 32^b below the concave edge 32^a, said extension being in the form of a segment which presents a convex edge 32^c 65 for the roller stud 30 to travel upon, and

this edge being part of the time concentric with the rock shaft 12. The bail arm 13^a operates in the usual manner with the cam plate 26 and the downward movement imparted to it by the roller stud 26^a on said cam plate serves in the present instance to actuate the rocker piece 32 immediately upon inauguration of an operation of the machine. Thus there immediately occurs a sharp camming action of the roller stud 70 30 against the concave edge 32^a of said rocker piece, said roller stud riding off said edge and onto the convex edge 32^c. This occurs while the upper rear convex section of the acting edge of the cam plate 26 is 75 traversing the roller 17^a of the type-carrier restoring bail and consequently occurs before there is any movement of the type-carrying levers. Therefore, the retraction of the closure yoke takes place before the type 80 carriers move, and the opening 7^b is fully uncovered in due time for projection therethrough of the type carriers, it being understood that the swing of the rocker piece 32 as effected by the above described camming 85 action of the roller stud 30, is of such extent as to cause full retraction of said yoke by the action of the straight edge of the rocker piece against the stud 33 (Fig. 2). As the first half cycle of operation of the machine 90 continues the roller stud 30 merely rides upon the edge 32^c of the rocker piece, which edge is then concentric with the rock shaft 12. When the parts reverse their motion, upon release of the operating handle 16, said 100 roller stud 30 travels back up said edge 32^c and then, when the aforesaid concentric section of the acting edge of the cam 26 returns to engagement with the roller 17^a, the roller stud 30 arrives at the upper end 105 of said rocker piece edge 32^c, and as the operation concludes the said roller stud 30 will pass upwardly beyond said edge and the closure yoke will be restored to normal, the concave edge 32^a of the rocker piece becoming reengaged with the roller stud 30. The type carriers will meantime have been 110 restored to their normal positions so that their upper ends are below the path of movement of the cover plate 11.

This cover plate may conveniently be utilized as a line finder and gage. It will be clear that its position is such as to perfectly adapt it to such purpose. Its rear edge is normally in close proximity to the ink ribbon where the latter overlies the paper passing around the platen, and said rear edge defines a line immediately below the last imprint. Furthermore the cover plate or shutter returns to such position in every operation of the machine and so is always ready to serve as a line finder. Its functioning in this respect, after the manner of devices of a similar character well known in the art, will be apparent from inspection of 115 120 125 130

Fig. 4. This plate may be marked as these line finders commonly are and as illustrated in Fig. 4, so as to facilitate the vertical alinement of the printing.

I claim:

1. The combination with the casing, type carriers, and actuating mechanism, said carriers adapted to be projected through an opening in the casing; of a movable closure for said opening, and means for retracting said closure automatically by said actuating mechanism as a preliminary to projection of the type carriers, and for restoring it to closing position as the operation of said actuating mechanism concludes.
2. The combination with the casing, type carriers, platen, and actuating mechanism, said carriers adapted to be projected through an opening in the casing adjacent to the platen; of a movable closure for said opening normally held in close proximity to the platen, and means for retracting said closure automatically by said actuating mechanism as a preliminary to projection of the type carriers, and for restoring it to closing position as the operation of said actuating mechanism concludes.
3. The combination with the casing, type carriers, and actuating mechanism, said carriers adapted to be projected through an opening in the casing; of a swinging closure

for said opening, a spring holding said closure over said opening, and means for retracting said closure automatically by said actuating mechanism as a preliminary to projection of the type carriers, and for restoring it to closing position as the operation of said actuating mechanism concludes.

4. The combination with the casing, type carriers, and actuating mechanism including an oscillatory member, said carriers adapted to be projected through an opening in the casing; of a movable closure for said opening, and means for retracting said closure by the oscillatory member of the actuating mechanism, with provisions for effecting the retraction at the beginning of the movement of said member and holding the closure retracted as movement thereof continues.

5. The combination with the apertured casing, type carriers, platen, and actuating mechanism including an oscillatory member carrying a roller; of a spring-held swinging closure for the aperture of the casing, and a cam rocker acted upon by the aforesaid roller and acting upon the closure, substantially as described.
